UNITED STATES PATENT OFFICE.

DANIEL PARKER, OF CALVERT, TEXAS.

THILL-COUPING.

SPECIFICATION forming part of Letters Patent No. 581,558, dated December 25, 1894.

Application filed March 3, 1894. Serial No. 502,208. (No model.)

To all whom it may concern:

Be it known that I, DANIEL PARKER, of Calvert, in the county of Robertson and State of Texas, have invented a new and Improved 5 Thill-Coupling, of which the following is a full, clear, and exact description.

My invention relates to improvements in couplings such as are used in attaching thills and poles to the axle of a vehicle; and the object of my invention is to produce a thill coupling of the greatest simplicity, strength and cheapness, which can be conveniently applied to any ordinary vehicle, which is arranged in such a way that rattling is positively prevented, and which, when the thills are dropped, permits them to be freely lifted from the coupling; also to a modified form of the device designed to prevent rattling only.

To these ends, my invention consists of a 20 thill coupling, the construction of which will be hereinafter described and claimed.

Reference is to be had to the accompanying drawings, forming a part of this specification, in which similar figures of reference indicate 25 corresponding parts in all the views.

Figure 1 is a sectional elevation of my improved coupling as applied to the thill and axle, the thill being shown in its raised position in which it is held when the carriage 30 is in use. Fig. 2 is a similar view, but with the thill dropped. Fig. 3 is a sectional plan on the line 3—3 of Fig. 1. Fig. 4 is a sectional elevation of a modified form of the device. Fig. 5 is a detail perspective view of the abutment plate which is secured to the 35 thill and is adapted to hold the anti-rattling block in place; and Fig. 6 is a broken detail view of a modified form of the coupling, with the abutment plate integral with the pole iron.

As illustrated, the axle 10 is of the usual kind, having secured to it the customary clip 11, which is provided with the usual base plate or bar 12, the plate or bar being of the usual kind, except that it is prolonged so that 40 its front end 13 projects forward beneath the lugs 14, which are arranged parallel with each other and are secured to the clip 11 in the usual way. The lugs 14 carry the coupling bolt 15 which extends transversely through 45 them in the customary manner, and this bolt is adapted to engage the knuckle 16 of the thill iron 17, which knuckle is made prefer-

ably in the form of a hook, as shown in Figs. 1 and 2, so that it may readily engage or be removed from the bolt 15; and the back of the 55 knuckle is thickened, as shown at 18, so that when the thill iron is raised to the position illustrated in Fig. 1, the thick or cam-like portion of the knuckle will press firmly against the anti-rattling block 20, and bind 60 the block in its place.

The thill iron 17 is secured to the thill 19 in the customary manner, and the anti-rattling block 20, which is of rubber, is inserted between the lugs 14 and behind the knuckle 65 16, resting on the prolonged front end 13 of the clip bar or plate 12. The block 20 is prevented from jumping out, by the abutment plate 21, which when the thill 19 is raised, extends directly across the top of the anti- 70 rattling block, the plate having a shank 22 which is arranged substantially at right angles to it, and it is longitudinally slotted, as shown at 23, to receive the bolt 24 by which it is fastened to the thill, this arrangement 75 also permitting the adjustment of the shank longitudinally of the thill, so that the abutment plate may be brought into the desired position with relation to the anti-rattling block 20.

It will be observed that when the thill is in its normal position for use, as illustrated in Fig. 1, the block 20 will be bound between the lugs 14, the knuckle 16 and the clip 11 on its sides, while at the top and bottom it will 80 be held by the abutment plate 21 and the end 13 of the clip plate so that the block cannot be displaced, and at the same time the thick side of the knuckle nips the block, which being resilient, holds the knuckle firmly against 85 the coupling bolt, and rattling and displacement are thus rendered impossible. When, however, the thill is dropped to the position shown in Fig. 2, the thinner part of the knuckle comes opposite the anti-rattling 90 block 20, which can then be easily removed, after which the knuckle may be lifted freely from its coupling bolt. Instead of making the knuckle in the form of a hook, as described above, it may be simply perforated 100 like the knuckle 16^a shown in Fig. 4 to receive the bolt, and then it is of course necessary to remove the bolt before removing the knuckle, but in this case the knuckle is

the same in principle, as it has the thickened back 18 adapted to impinge on the anti-rattling block 20.

In Fig. 6, I have shown a pole iron 25, having a knuckle like the one shown in Fig. 1, and an abutment plate 21^a formed integral with the pole iron and projecting above the block 20.

I am aware that it is not broadly new to use the anti-rattling block and the thickened knuckle, but my arrangement of the abutment plate and clip plate 12 serves, in combination with the other parts of the coupling, to prevent any possible displacement of the anti-rattling block, and this combination is believed to be new.

Having thus described my invention, I claim as new and desire to secure by Letters Patent—

20 1. A thill coupling, comprising an axle clip having forwardly projecting lugs, and a base plate having its front end projecting beneath the lugs, a resilient block whose lower end rests on the said base plate between the lugs, 25 the thill iron having a knuckle thickened at

the back and adapted for pivotal connection with the said lugs in advance of the resilient block, and an abutment plate on the back of the thill projecting beyond the back of the knuckle and above the yielding block, substantially as described.

2. A thill coupling, comprising an axle clip having forwardly projecting lugs and a base plate having its front end projecting beneath the lugs, a resilient block whose lower end 35 rests on the said base plate between the lugs, the thill iron having a knuckle thickened at the back and adapted for pivotal connection with the said lugs in advance of the resilient block, and an abutment plate held on the 40 rear surface of the thill and adjustable longitudinally thereof, the said abutment plate projecting beyond the back of the knuckle and above the yielding block, substantially as described.

DANIEL PARKER.
